(57) **CLAIM**

The ornamental design for a display screen with animated graphical user interface, as shown and described.

DESCRIPTION

The patent file contains at least one drawing executed in color. Copies of this patent with color drawings will be provided by the Office upon request and payment of the necessary fee.

FIG. 1 is a front view of a first image of a display screen with animated graphical user interface;

FIG. 2 is a front view of a second image thereof;

FIG. 3 is a front view of a third image thereof;

FIG. 4 is a front view of a fourth image thereof; and,

FIG. 5 is a perspective view showing the design of FIG. 1 applied thereto in a state of use.

The appearance of the display screen with animated graphical user interface transitions sequentially between the images shown in FIGS. 1 thru 4. The process or period in which an image transitions to another forms no part of the claimed design.

The outermost broken line showing of a display screen illustrates portions of the article and does not form part of the claimed design. The broken lines showing an electronic device in FIG. 5 illustrate environmental subject matter, and do not form part of the claimed design.
